CASING HEAD

John A. Jesson and Samuel Clyde Kyle, San Francisco, Calif., assignors of seventy-six one-hundredths to said Jesson and twenty-four one-hundredths to R. A. Watson, San Francisco, Calif.

Application July 11, 1939, Serial No. 283,800

4 Claims. (Cl. 166—14)

Our invention relates to well fittings and has particular reference to a casing head finding particular utility when employed on deep pumping wells such as oil wells.

- 5 In the oil producing industry the very deep wells employed are lined throughout the greater part of their length with a casing which protrudes above the ground surface. If the well is not of the flowing type so that it is necessary to operate 10 pumping equipment in order to remove the liquid from the well, a pump is placed near the bottom of the well and connected by a sucker rod string to a reciprocating mechanism located at the ground surface and adapted to reciprocate the pump 15 plunger to effect the desired pumping operation.

In case such pumping equipment is employed, it is necessary to separate the pumped fluid from whatever gases may be generated within the well or discharged upwardly through the casing and 20 for this purpose it is common practice to employ a string of flow tubing disposed substantially concentrically within the casing and connected to the pump cylinder located at or near the bottom of the well.

25 The termination of these three elements; namely, the casing, the flow tubing, and the sucker rods at the ground surface give rise to the problems of providing separate discharge for the gases and the pumped liquids, means for supporting 30 the weight of the string of flow tubing and the pump mechanism carried thereon, and a means to permit the passage of the sucker rods through both the oil conveying spaces and the gas conveying spaces without permitting cross flow between these spaces. Furthermore, the mechanism employed in the top of the casing must be 35 so constructed as to permit the ready removal of the sucker rods, the flow tubing and the pumping mechanism which is disposed below the ground 40 surface.

Prior to our invention, it has been common practice to employ three separate sets of ground surface equipment for performing these various functions. This equipment included a casing 45 head which was secured to the upstanding end of the casing and which provided a discharge outlet for gas which collected between the casing and the flow tubing. To the casing head was clamped a casing top which served the dual purpose of sealing off the flow tubing from the gas discharge 50 space and for supporting the entire set of tubing string and pump carried thereby upon the casing. A tubing head was then affixed to the top of the casing top and included means for discharging 55 the flow of pumped fluid into suitable flow lines

and a means for providing a seal or packing gland between the sucker rods and the flow tubing.

This present method of providing the necessary facilities at the ground surface of a pumping well is characterized by the primary disadvantage of 5 employing a great many separate parts which give rise to a high cost of maintenance and the introduction of many possibilities for accidents and trouble through the many interconnections employed between these various parts. Furthermore, the employment of such a relatively large 10 number of parts caused the initial cost of installing such ground surface equipment to be very high.

It is accordingly an object of our invention to 15 avoid the above noted disadvantages by providing a well fitting combining a single unit the functions of a casing head, casing top and tubing head.

It is also an object of our invention to provide 20 a well fitting or casing head of the character set forth in the preceding paragraph which employs a single means for carrying the weight of the tubing string and for sealing between the tubing and the interior of the well casing.

It is a further object of our invention to provide 25 a casing head of the character set forth in the preceding paragraph which includes a means for locking the tubing within the casing head to prevent axial movement thereof.

It is also an object of our invention to provide 30 a casing head of the character set forth in the preceding paragraph which includes an externally accessible means for adjusting the seal between the flow tubing and the gas conducting space 35 thereabout.

It is an additional object of our invention to provide 40 a casing head of the character set forth in the preceding paragraphs which includes separate fluid and gas discharge outlets.

It is also an object of our invention to provide 45 a casing head construction of the character set forth in the preceding paragraphs with a means for passing the sucker rods from the interior of the flow tubing to the exterior of the casing head and sealing to prevent either liquid or gas flow.

It is also an object of our invention to provide 50 a casing head of the character set forth in the preceding paragraphs which includes a single set of securing devices so constructed that removal of such single set permits the removal of the sucker rods and the flow tubing from the well without removing the casing head therefrom.

Other objects and advantages of our invention 55 will be apparent from a study of the following

specifications, read in connection with the accompanying drawing, wherein:

Fig. 1 is an elevational view partly in section illustrating the details of construction of the preferred form of casing head of our invention;

Fig. 2 is a view similar to Fig. 1 showing the manner in which the various parts are removed to permit removal of the tubing string from the well; and

10 Fig. 3 is a horizontal section taken substantially along the line III—III of Fig. 1 to illustrate the relative location of the securing means employed and the clamping means for adjusting the seal between the tubing string and the gas discharge 15 space.

Referring to the drawing, we have illustrated in Fig. 1 the preferred embodiment of our invention as comprising a casing head body 1 which is adapted to be tightly secured to the upper end 20 of a casing string 2 by any suitable means such as screw threads 3. The casing head body 1 is provided with one or more hubs 4 which are bored and internally threaded as indicated at 5 to provide a connection to a gas discharge tube, 25 the bore 5 communicating with a cavity or space defined by the interior of the casing head body 1.

In order that the casing head body 1 may be employed also for holding and supporting the weight of a string of flow tubing 6, we provide an 30 annular inwardly extending ledge 7 which is provided with a substantially plane upper face 8. A supporting ring 9 having an exterior diameter substantially equal to the interior diameter of the casing head body 1 is placed within the casing 35 head in a position resting upon the plane face 8 defined by the flange or ledge 7. The supporting ring 9 is provided with an internal bore 10 adapted to pass the body portion of a tubing hanger 11 which is secured in the conventional fashion by 40 screw threads 12 to the upper end of the flow tubing 6. The bore 10 through the ring 9 is counterbored as indicated at 13 to provide a substantially plane radial ledge or seat 14 adapted to be engaged by a similar complementary flange 15 45 ordinarily formed on the tubing hanger 11.

It will be observed that the weight of the string of flow tubing 6 is, in this fashion, carried by the casing head body 1 since downward movement of the supporting ring 9 is prevented by 50 engagement of the ring with the flange 7 and in a similar manner downward movement of the flow tubing 6 and the tubing hanger 11 secured thereto is prevented by engagement of the flange portion 15 thereof with the bottom 14 of the 55 counterbore 13.

In order to provide a gas tight seal between the flow tubing 6 and the annular gas space between the exterior of the flow tubing 6 and the casing 2 which communicates with the gas discharge 5, we prefer to employ gaskets 16 and 17 between the ring 9 and the flange 7 and between the flange 15 and the bottom 14 of the counterbore 13. In this fashion the annular ledge 7, the supporting ring 9, and the tubing hanger 11 operate as a partition dividing the casing head body 1 horizontally in such fashion that fluid pumped through the interior of the flow tubing 6 is confined to the space above this partition.

In order that the fluid which is pumped through 70 the flow tubing 6 may be transmitted to storage tanks or pumping units as desired, we provide one or more hubs 18 which are provided with a threaded bore 19 communicating with the interior space within the casing head body 1 above the 75 end of the tubing string 6. The bore 19 may, if

desired, be threaded to receive a correspondingly threaded end of a flow pipe.

The casing head body 1 is provided with an opening 20 at its upper end of a diameter sufficient to pass the supporting ring 9 so that the flow tubing 6 and the supporting ring 9 may be removed upwardly and clear of the casing head body 1 without requiring that the connection between the body 1 and the casing 2 be disturbed. The opening 20 is preferably closed by 10 means of a top plate 22 which is secured to the upper end of the casing head body 1 by a single set of securing means which may comprise bolts 23 passed through the top plate 22 and threaded 15 engaged with the upper end of the casing head 15 body 1. The top plate 22 is preferably drilled and tapped to receive a plurality of adjusting or clamping bolts 24 which extend downwardly through the top plate 22 in a position to engage an upper clamping ring 25. The clamping ring 20 25 is made circular in shape having an outside diameter substantially equal to the outside diameter of the aforementioned supporting ring 9 and is provided with a central bore 26 adapted to pass over the upper end of the tubing hanger 25 11.

It will be observed that rotation of the clamping screws 24 to move them downwardly through the threaded connections with the top plate 22 will cause the lower ends thereof to bear against 30 the upper clamping ring 25 and force the same downwardly against the upper surface of the tubing hanger flange 15 and operate to clamp the supporting ring 9 between the tubing hanger 11 and the flange 7. The heads of the adjusting 35 screws 24 being disposed exteriorly of the casing head body 1 permits the adjustment of the seal which is provided by the gaskets 16 and 17 without requiring any disassembly of the device.

Inasmuch as the pump which is carried by the lower end of the string of flow tubing 6 is ordinarily operated through a string of sucker rods, the upper section thereof or polished rod 27 must pass from within the interior of the flow tubing 6 to mechanism located exteriorly of the casing 40 head body 1 which is adapted to provide the necessary reciprocating motion to the polished rod 27 to effect the pumping operation. A liquid tight seal may be provided between the polished rod 27 and the fluid space defined within 45 the casing head body 1 by providing a packing gland of conventional construction which may include a cylindrical body portion 28 threaded 50 engaged with the top plate 22. Within the bore of the body portion 28 is disposed conventional 55 packing 29 adapted to be clamped into sealing engagement with the exterior surface of the polished rod 27 by means of a clamping element 30 60 cooperating with an adjusting cap 31.

Attention is called to the fact that the removal 60 of the single set of securing means 23 permits the removal of the top plate 22 so that the string of sucker rods may be removed and so that the entire tubing string may be removed from the casing 65 without requiring other dismantling operations to be performed on the casing head of our construction.

The manner in which the parts are disassociated at the time the tubing string is removed is illustrated in Fig. 2. In this figure the polished rod 27 and the string of sucker rods secured thereto has been removed by removing the top plate 22. Any suitable hoisting device may be engaged with the upper end of the tubing hanger 11 and a hoisting force applied to raise 75

the tubing string 6. Raising of the tubing string 6 lifts the tubing hanger 11 from the supporting ring 9 on which it is carried, upward movement of the tubing hanger 11 also operating to remove from the casing head 1 the upper clamping ring 25.

From the foregoing it will appear that we have provided a new and simple casing head construction which performs all of the functions 10 previously performed by a casing head, casing top and tubing head and which is composed of a minimum number of parts and interconnections between these parts, thus providing for a low cost manufacture and trouble-free maintenance of 15 the device.

While we have shown and described the preferred embodiment of our invention, we do not desire to be limited to any of the details of construction shown or described herein, except as 20 defined in the appended claims.

We claim:

1. In a casing head for use on the upper end of a well casing enclosing a string of flow tubing terminating in a flanged tubing hanger, the combination of: a casing head body having means for attachment to the upper end of a well casing; a cavity in said body; a support formed on said body and extending into said cavity; a supporting ring resting upon said support and having an 30 opening for passing said tubing; seat means on said ring for receiving the flange of said tubing hanger to support said string of tubing within said casing, said support, ring and flange defining a partition dividing said cavity into a gas space 35 communicating solely with said casing and a liquid space communicating solely with said tubing; an opening in the top of said body of a size sufficient to pass said ring; and removable closure means for closing said opening, whereby removal of said closure means permits removal of said ring and said flow tubing.

2. In a casing head for use on the upper end of a well casing enclosing a string of flow tubing terminating in a flanged tubing hanger, the combination of: a casing head body having means for attachment to the upper end of a well casing; a cavity in said body; an annular ledge formed on said body and extending into said cavity; a supporting ring resting upon said ledge and having 50 an opening for passing said tubing; seat means on said ring for receiving the flange of said tubing hanger to support said string of tubing within said casing, said ledge, ring and flange defining a partition dividing said cavity into a gas space 55 communicating solely with said casing and a liquid space communicating solely with said tubing; sealing means interposed between said

flange and said seat and between said ring and said ledge to prevent passage of fluid between said gas space and said liquid space; and clamping means carried by said body in a position disposing a part exteriorly of said cavity and another part in engagement with said flange for clamping said sealing means.

3. In a casing head for use on the upper end of a well casing enclosing a string of flow tubing terminating in a flanged tubing hanger, the combination of: a casing head body having means for attachment to the upper end of a well casing; a cavity in said body; an annular ledge formed on said body and extending into said cavity; a supporting ring resting upon said ledge and having 10 an opening for passing said tubing; seat means on said ring for receiving the flange of said tubing hanger to support said string of tubing within said casing, said ledge, ring and flange defining 15 a partition dividing said cavity into a gas space 20 communicating solely with said casing and a liquid space communicating solely with said tubing; sealing means interposed between said flange and said seat and between said ring and said ledge to prevent passage of fluid between said gas 25 space and said liquid space; a clamp plate resting upon said flange and having a bore aligned with said tubing; and clamp means carried by said body in a position disposing a part exteriorly 30 of said cavity and another part in engagement with said clamp plate for clamping said sealing means.

4. In a casing head for use on the upper end of a well casing enclosing a string of flow tubing terminating in a flanged tubing hanger and having a polished rod extending upwardly therethrough, the combination of: a casing head body having means for attachment to the upper end of said well casing; a cavity in said body; an annular ledge formed on said body and extending 35 into said cavity; a supporting ring resting upon said ledge and having an opening for passing said tubing; seat means on said ring for receiving the flange of said tubing hanger to support said string of tubing within said casing, said ledge, 40 ring and flange defining a partition dividing said cavity into a gas space communicating solely with said casing and a liquid space communicating solely with said tubing; an opening in the top of said body of a size sufficient to pass said ring; 50 removable closure means for closing said opening; an opening in said closure means for passing said polished rod; and packing means interposed between said polished rod and said closure means to prevent escape of liquid through said opening. 55
